UNITED STATES PATENT OFFICE.

FRANK H. DERBY, OF ERIE, PENNSYLVANIA, ASSIGNOR TO ERIE FOUNDRY COMPANY, OF ERIE, PENNSYLVANIA, A CORPORATION OF PENNSYLVANIA.

POWER HAMMER.

Application filed September 13, 1926. Serial No. 135,137.

Power hammers are ordinarily provided with guides which guide the head in its movement. Parts of these guides, particularly that part of the guide which controls the head at the moment of impact is subject to severe wear and severe strains. The present invention be designed to provide a means whereby this part of the guide may be made removable and is of such length that it is uncovered with the hammer in its extreme upper position so that the renewals may be made of these guide parts without taking down the hammer as a whole. Features and details of the invention will appear from the specification and claims.

The invention is illustrated in the accompanying drawings as follows:

Fig. 1 shows a side elevation of a hammer.

Fig. 2 a face of one of the guide posts forming a part of the frame of the hammer.

Fig. 3 a section on the line 3—3 in Fig. 1.

Fig. 4 a section on the line 4—4 in Fig. 1.

Fig. 5 a side view of the removable guide member detached.

1 marks the base of the hammer, 2 the guide posts, 3 the cap, 4 board actuating rolls, 5 gears driving the rolls 4, 6 a gear operating the gears 5, 7 drive pulleys, and 8 boards operated by the rolls 4, and 9 the hammer head. As shown these parts are such as are common in what is known as a board hammer but it will be understood that this is merely an exemplification of the mechanism for actuating the head and the invention is applicable to any type of drop power hammer.

Head guides 2^a are formed on the faces of the posts 2 and operate in one of the guide grooves 10 in the sides of the head. The guides 2^a are extended by means of removable guide blocks 11 which are arranged in sockets 12 in the faces of the posts 2. The blocks preferably have a plural set of guide ribs on their faces which engage the walls of the grooves 10 in the head while the guide groove 2^a on the past is simply a single guide rib. This, however, is simply as a matter of economy as the single rib for the upper or idling part of the travel of the head is ample for guiding the head in this part of its travel while the plural guide ribs of the lower working part of the guide receive

the shock and control the side movement of the hammer head.

The blocks 11 are provided with the undercut grooves 13 and bolts 14 are arranged in these grooves and extend through the post and are secured by nuts 15 on the outer faces of the posts. Thus the removable guide block is securely clamped in the socket so as to hold it in place under the severe strains to which it is subjected.

When it is desired to renew the removable guide blocks the head is drawn up to a position above the removable guide parts and the removable guide portions may be then readily removed and renewed without taking down any other part of the hammer. Further the lower parts of the guides receive the real wear and strain in operation and by making these parts removable they may be formed, if desired, of a different metal than that of the part 2^a so as to better sustain the wear and strain of the lower part of the travel.

What I claim as new is:

1. In a hammer, the combination of guide posts; a head; means actuating the head; and a head guide on the post having its lower marking part removable, said removable part being uncovered by the head within the limits of its travel.

2. In a hammer, the combination of guide posts having upper head guides thereon and guide sockets therein; removable lower working head guides in the sockets and extending guides on the posts; means securing the removable guides in the sockets; and a head operating in said guides and uncovering the lower removable parts of said guides within the limits of its travel.

3. In a hammer, the combination of guide posts having single ribbed upper guides in the faces of the posts; removable lower working guides in continuation of the upper guides on the posts, said removable working guides having a plurality of guiding ribs; a head operating in said guides and uncovering the removable working guides within the limits of its travel; and means actuating the head.

In testimony whereof I have hereunto set my hand.

FRANK H. DERBY.
